UNITED STATES PATENT OFFICE

149,971

DESIGN FOR A HAND WASHBOARD

Jean O. Reinecke, Oak Park, Ill., assignor to Barnes & Reinecke, Chicago, Ill., a corporation of Illinois

Application August 21, 1946, Serial No. 132,681

Term of patent 14 years

(Cl. D49—1)

To all whom it may concern:

Be it known that I, Jean O. Reinecke, a citizen of the United States of America, residing at Oak Park, in the county of Cook and State of Illinois, have invented a new, original, and ornamental Design for a Hand Washboard, of which the following is a specification, reference being had to the accompanying drawing, forming part thereof.

Fig. 1 is a perspective view of a hand washboard showing my new design;

Fig. 2 is a bottom plan view thereof; and

Fig. 3 is an end elevation of the same.

I claim:

The ornamental design for a hand washboard, as shown.

JEAN O. REINECKE.
